UNITED STATES PATENT OFFICE

145,681

DESIGN FOR A VACUUM CLEANER ATTACHMENT

Clifford Brooks Stevens, Milwaukee, Wis., assignor to Modern Hygiene, Inc., Boston, Mass., a corporation of Massachusetts

Application December 22, 1945, Serial No. 125,010

Term of patent 14 years

(Cl. D9—2)

To all whom it may concern:

Be it known that I, Clifford Brooks Stevens, a citizen of the United States, residing at Milwaukee, in the county of Milwaukee and State of Wisconsin, have invented a new, original, and ornamental Design for a Vacuum Cleaner Attachment, of which the following is a specification, reference being had to the accompanying drawing, forming part thereof.

I claim:

The ornamental design for a vacuum cleaner attachment, as shown.

CLIFFORD BROOKS STEVENS.
